UNITED STATES PATENT OFFICE

2,396,421

MACHINE FOR LEATHER ROLLING AND
SETTINGFrederick W. Henning, Cincinnati, Ohio, assignor
to The American Oak Leather Company, Cincinnati, Ohio, a corporation of Ohio

Application April 27, 1944, Serial No. 533,078

9 Claims. (Cl. 69—46)

My invention relates to machines for rolling and setting leather.

In the art, the rolling and setting of leather has ordinarily been carried out by a manually controlled machine in which an operator holds the edges of the leather piece to be rolled and set on a table which is elevated by a foot treadle to a desired position to be engaged by a ball or roller carried by a rocking beam which swings back and forth in a predetermined arc over the table. With each sweep of the arc of the rocking beam the roller engages the upper surface of the leather piece and rolls across it.

The operator pulls and pushes the leather piece while the roller is carried back and forth across it by the oscillations of the rocking beam. When the roller is at one end of its stroke and is at rest for a brief instant, the operator moves or slightly rotates the piece on a pivot represented by the point at which the roller is at rest. Then the roller traverses a different area of the piece on its return sweep. Then when the roller is at the other end of its stroke the operator moves or slightly rotates the piece again on a pivot represented by the rest point at that end of the stroke of the roller. Thus by an alternate twisting of the piece first with one hand and then the other, the entire area of the piece is finally traversed and rolled by the roller. At no time during this rolling is the movement of the piece substantially at right angles to the direction of the oscillations of the rocking beam.

The necessity for rolling and setting leather is that the previous treatments of the hide and the pieces into which it is cut leave the leather with the grain side covered with little cavities or hair follicles. Further the fat of the animal from which the hide comes causes what are called fat wrinkles.

The purpose of rolling and setting the leather is to close up the follicles, smooth out the wrinkles and compact the hide so that it will have a substantially uniform firmness. It has been found that straight downward compression applied to the different areas of a leather piece does not do a satisfactory job and that it is only when the compressing is accompanied by a rolling movement of the compressing mechanism that the various objectives are accomplished.

The mechanisms now in use and which depend on the skill of the operator in manually moving the leather piece over the table require exhausting labor and there is a constant danger that the piece will slip and the hand of the operator will be crushed under the roller.

It is to obviate the accident risk, to reduce the labor involved and to more perfectly roll and set the leather that my invention is directed.

It is my object to provide in a mechanism which requires no more than a "feed in" and "take out" operation for moving the leather piece through the machine and during its movement to roll and compress the piece substantially at a right angle to the direction of feeding movement.

It is a further object to roll and compress each piece during its feeding movement by rollers of varying width so that by the time the leather piece has been fed through the machine it will have been rolled and compressed in narrow bands or areas and in wider bands. Preferably the operation in which the thin bands are rolled and compressed will be the initial treatment, this rolling and pressing in thin bands being followed by subsequent treatment of wider bands of the leather piece as it moves through the machine but such sequence is not essential.

While the movement of a piece of leather and the rolling of the piece by successive application of rolling pressure distributed in bands of even width accomplishes a satisfactory result, my invention in the application of rolling pressure first in narrow bands and then in wider bands creates a greatly improved result, particularly in smoothing out the fat wrinkles.

The machine is entirely automatic in its actual operation and defects caused by improper manipulation of a leather piece by an unskilled operator are avoided.

The grading of leather and incidentally its availability for a wide range of usefulness is dependent on the success of the rolling and setting operation so that an improvement in the quality of work done is a commercial advantage of consequence.

It is not merely to doing the job with foolproof mechanism and which is labor saving, but it is to doing the job better and thus increasing the yield of better quality leather, that my mechanism is directed.

In the drawings in which I have shown a preferred mechanism for accomplishing my various purposes—

Figure 1 is a perspective view of the complete machine.

Figure 2 is an end elevation of the machine of Figure 1 with parts in section, as would appear along the lines 2—2 of Figure 1, the driving means being shown somewhat diagrammatically in dotted lines.

Figure 3 is a sectional view as would appear on

lines 3—3 of Figure 2, the cross rolling and setting operation at the delivery end of the machine only being shown.

Figure 4 is a side elevation showing the initial cross rolling and setting operation where the narrow bands of the leather piece are first exposed to the transverse rolling pressure.

Figure 5 is a plan of the transverse carriage shown in side elevation of Figure 4.

Figure 6 is an end elevation of the carriage shown in Figures 4 and 5.

Figure 7 is a side elevation of the second roller carriage from the receiving end of the machine, the width of the bands or areas receiving rolling pressure being increased by a three roller carriage as compared to the initial seven roller carriage.

Figure 8 is a plan, part in section, on the lines 8—8 of Figure 7.

Referring now to the drawings (particularly Figure 1) 1 indicates the frame of the machine. As shown, it may be made of channel and angle bars and preferably assembled by welding into a complete support. Along the top on each side is a channel member 2. Spaced below the frame member 2 there are channel irons 3 which support the various mechanisms which perform the applications of rolling pressure on the leather piece.

Mounted on the base of the frame are channel iron members 4, which with the base members carry the driving mechanism. This consists of a series of eight driving discs 5 assembled in pairs, and supported between pairs by bearing standards 6 which carry the driving shaft 7. This driving shaft 7 extends beyond the driving discs at each end of the machine, and is also supported by bearing standards 6. On the shaft 7 are mounted the driving pulleys 8 and 9. Mounted on a suitable base, extending the length of the machine, is a countershaft 10 mounted in suitable bearing standards 11.

At each end of the countershaft 10 are driving pulleys 12 which drive the pulleys 8 and 9 by means of belts 13, 14. Mounted on the countershaft 10 is a larger driving pulley 15 which may be mounted at either end or in the middle of the length of the shaft 10. It is connected by belt 15a to a source of power (not shown). The assembly described furnishes the support and the power for driving the various mechanisms now to be described for feeding the leather piece and exerting rolling pressure on it.

Looking now at Figure 1, it will be seen that the first element to be driven is a pair of feed rolls 16 and 17, mounted in bearings 58 and 59 housed in stirrup frames 18 and 19. These stirrup frames are bolted at the bottoms to frame member 3 (as best seen in Figure 3). The shaft of the lower roll 17 extends through a lower bearing in the stirrup frame and has mounted on its outer end a bevel pinion gear 20. This gear meshes with driven bevel gear 21. There are, as will be observed from Figure 1, five sets of feed rollers equivalent to the feed rollers 16, 17.

At a point near the rear end of shaft 7 is mounted a sprocket gear 21a. On the frame 1, mounted in bearings 22 and 23, there is a short countershaft on which is mounted a driving sprocket wheel 24. Connecting the sprocket gear 21a on the shaft 7, and the sprocket wheel 24 on the countershaft there is a sprocket chain 25. Also mounted on the countershaft is a small sprocket 26.

Mounted in bearings 21 along the frame 1, there is a drive shaft 28 which extends along the

length of the machine. Mounted near the rear end of shaft 28 there is a large sprocket wheel 29, and the sprockets 26 and 29 are connected by a sprocket chain 30.

The combination just described furnishes a driving means from the power supply through the shaft, countershaft and sprockets to the shaft driving the bevel gears 21 and the bevel gear pinions 20 mounted on the bottom roll of each pair of leather feed rolls.

As will be seen in Figure 2 on the right hand end of the feed rolls 16 and 17, there are a pair of gears 31 and 32. These gears transmit driving power from the lower roll 17 to upper roll 16. Since the drive for all five sets of feed rolls is the same, it should be understood that mention of driving means for any given set of feed rolls is the same as that described for the first set as the "feed in" end.

Observing now Figures 1, 2 and 3, it will be noted that at spaced intervals between the feed rolls and transversely disposed are pairs of channel iron beams 33 and 34. These beams are secured to the top frame member 2 by angle iron brackets 35 which are secured to the frame member 2 by bolts 36. The transverse channel beams are secured in the brackets 35 by bolts 37 which pass through enlarged holes in the bracket members 35, and are threaded into the beams 33 and 34. A series of adjusting screws 38 (Figures 1 and 2) at the top and bottom of beams 33—34 bear against the beam members 33—34 near their ends. By loosening the bolts 37 slightly and turning the adjusting screws 38, the beams 33—34 may be adjusted up or down, to level or correct the distance to or from work passing under the pressure roller assemblies carried by the beams 33 and 34.

Mounted on the beams 33 and 34 are a series of transversely traveling carriages or pressure heads. These carriages are formed from a pair of triangular shaped side plates 39—40 and an inner pair of lesser sized triangular shaped plates 41 and 42 (Figure 3). The outer and inner plates 45 are separated by bushings 43. A series of rollers 44 are held in operative condition by bolts 45. Welded to the sides of inner plates 41—42 are brackets 46, mounted between and near each end of brackets 46 are side bearing rollers 47 which have a running, guiding contact with the beams 33 and 34. The rollers 44 have a running contact, top and bottom, with the beams 33 and 34.

The construction of the carriage thus far described makes a structure which has a minimum of side sway, while moving forward or back on the beam members 33 and 34.

Mounted in the bottom right and left corners of the triangular carriages are shafts 48. Carried by these shafts are a series of arms 49, these arms carrying a series of rollers 72 (Figures 4, 5, 6). The arms 49 to the left carry four rollers and the arms to the right carry three rollers, in this particular carriage.

Mounted a short distance above the arms 49 is a plate 51, welded to the outside plates 39 and 40 of the carriage. On each pair of the arms 49 is a second plate 52 welded to the arms. Interposed between the plate 51 and plates 52 are adjustable springs 53. These springs provide a resilient pressure for the various groups of rollers.

Mounted at the right hand edge of the traveling carriages, are shafts 53a extending from side to side of the carriages, and mounted on the shafts are connecting rods 54 (Figures 2, 4 and 5).

These connecting rods 54 are connected to swinging arms 55 which are pivoted at 56 to a base plate. Adjustably connected to the arms 55 are links 56a, which in turn are connected to wrist pins 57a, mounted in the driving discs 5.

The rotation of the shaft causes the links 56a to pull the arms 55 to and away from the frame of the machine which in turn causes arms 55, by reason of their connection to the carriages, to move the carriages to and fro on the beams 33 and 34, thus causing the series of rollers in the various carriages to perform the rolling pressure operations on the leather piece as it is fed forward through the machine by the feed rollers.

As shown in Figure 3, the feed rolls 16 and 17 are mounted in bearing boxes 58 and 59 in the stirrup frame. The top bearing box of the feed rolls 16, has secured to it a rod 60, which is threaded in a boss on the top of the bearing box. The rod 60 extends upward passing through the stirrup frame and is capped by a pair of lock nuts 61. Surrounding the rod 60 and in slidably contact therewith is a bushing 62. The bushing has a threaded outer surface for part of its length and an annular boss 63 at its top which has spanner wrench holes spaced around its circumference. The boss 63 bears against the inner surface of the stirrup frame. Springs 64 surround the rods 60 and have a bottom bearing on the bearing box 58. The rods 60 contact the nuts 65. The nuts 65 are formed with squared portions which fit loosely in the stirrup frames. To adjust the tension of the springs 60 and increase the pressure of the feed rolls, a spanner wrench is inserted in the holes of the boss 63 and the bushing 62 is screwed up or down in the nut 65, thus increasing or decreasing the spring tension. Resistance to the resulting thrust of the spring adjustment is taken up by the stirrup frames, and the square shape of the bottom of the nut 65 prevents its turning due to its close fit in the stirrup frames 18 and 19.

Referring to Figure 3, it will be noted that at spaced intervals there are inverted cross iron channel bars 67. These channel bars are preferably welded to the supporting channel bar 3, blocks 68 being interposed between the channel bars 67 and the stirrup frames to furnish clearance for the feed rolls.

On the top of the bars 67 are table plates 69, preferably made of a heavy brass. These tables are fastened to cross bars 67 by welding or other suitable means. The table plates are slightly below the "pinch" of the feed rolls 16 and 17 which facilitates the entrance of the leather sheet into the pinch of the feed rolls.

Across the face of the upper feed roll 16 there is a deflector bar 70 which is supported at its outer ends on blocks to provide a space between the floor plate and the deflector bar for travel of the leather sheet marked X, on its way through the machine. These deflector bars prevent any wrapping of the leather sheet around the feed rolls 16 and the floor plate 69 is fitted close enough to the roll 17 to act as a deflector for the roll 17.

The traveling carriages 71, or pressure head, which has been described is preferably located at the feed end of the machine. It consists, as has been explained, of a group of seven comparatively narrow rollers 72 so spaced that the rollers of one group overlap the path of travel of the other.

The purpose of the smaller rollers is to enable rolling out of small depressions and wrinkles. The rollers are moved rapidly forward and back

as the carriage travels across the width of the incoming advance of a leather piece. As the advancing leather passes the second set of feed rolls, it is "set" by a second traveling carriage 73 and its rollers are preferably like the pressure head shown in Figures 7 and 8. The construction is the same as that of carriage 71 with the exception that there are only three rollers, two on one side of the carriage and one on the other. As in connection with the three rollers overlapping the path of travel of the four rollers in the pressure head 71, the single roller overlaps the gap between the two rollers and again the result desired is accomplished by reason of the roller's ability to reach wrinkles and depressions, not probable at this stage of the setting of the leather with a single wide roller.

Referring to Figures 1 and 3 there will be seen the third and fourth traveling carriages 74 and 75 with their single rollers. In these carriages there is only one single roller, which as shown extends the full width of the carriage. The carriage construction is otherwise the same as those previously described, except that the arms 49 extend forward so that the single rollers 75 and 77 are at the center of the carriages. Further the size and strength of the springs 53 is increased. These single roller heads perform the final setting and rolling operation and bring the surface of the leather to a smooth compact finish.

The particular arrangement described and illustrated and consisting of one seven roller pressure head, one three roller pressure head and two single roller pressure heads is not essential. Other arrangements of pressure heads with different numbers of rollers such as 9, 7, 5, 3 may also be used. It is even not essential for the practice of my method to have some heads with a plurality of narrow rollers, though I have found in the operation of my machine that this is desirable.

While the feed of pieces of leather flatwise through the machine may be an intermittent feed, wherein the piece stops during the intervals when rolling pressure is applied to the piece transverse to the direction of feed, first in narrow bands, as for example with the seven roller head and then in successively wider bands as with the three roller head and single roller heads, I have found that if the rate of feeding movement is reduced to a ratio of from about 1 to 20 and over, as compared with the rate of movement of the pressure heads that a continuous feeding movement, as in the machine illustrated, may be successfully carried out. Thus with a rate of feeding movement of 10 feet per minute and a transverse application of rolling pressure by the pressure roller heads at a rate of 200 ft. per minute or more, the slippage of the piece during the application of pressure by the pressure roller heads causes a better smoothing out of the fat wrinkles than if the piece was stopped, as it could be with an intermittent feed, during the application of the rolling pressure.

Occasionally a single pass through the machine will not result in a satisfactory surface finish. In such event, it is a simple matter to put the unsatisfactory pieces to one side and feed them through the machine another time, or to set up additional pressure heads and feed rolls.

As far as I am advised, the continuous feeding of a piece of leather while applying rolling pressure at a so much greater speed than that of the feed, at right angles to the direction of feed, that there need be no stoppage of the feed, involves a hitherto unsuggested plan of operation,

Further the applying of rolling pressure, first by a set of narrow rollers arranged in a composite interspaced arrangement, and which in fact, roll the leather in a transverse band equal to the width of the assembly, involves a novel principle which is particularly effective in smoothing out fat wrinkles.

While I have illustrated these novel principles in an automatically operative machine, the same principle could be carried out in a hand manipulated operation where certain operators pulled a leather piece over a table and other operators applied the rolling pressure substantially at a right angle to the direction of pull. While such an operation would accomplish the purposes of my invention to a degree, it would not compare favorably with the results obtained by using the machine.

Having thus described my invention, what I claim as new and desire to secure by Letters Patent is:

1. In a leather rolling and setting machine, a series of pinch feed rollers provided with means for rotating same, and a series of pressure heads carrying rollers which exert rolling pressure against the leather as it is fed, provided with means for oscillating said pressure heads at substantially right angles to the direction of feeding movement of the pinch rollers.

2. In a leather rolling and setting machine, a series of spaced pinch feed rollers provided with means for rotating same, and a series of pressure heads carrying rollers arranged intermediate the sets of pinch feed rollers which exert rolling pressure against the leather as it is fed, and means for oscillating said pressure heads at substantially right angles to the direction of feeding movement of the pinch rollers.

3. In a leather rolling and setting machine, a series of spaced pinch feed rollers provided with means for rotating same, and a series of pressure heads carrying rollers arranged intermediate the sets of pinch feed rollers which exert rolling pressure against the leather as it is fed, and means for oscillating said pressure heads at substantially right angles to the direction of feeding movement of the pinch rollers, at a rate of speed of about twenty times or more as fast as the feeding rate of the pinch feed rollers.

4. In a leather rolling and setting machine, a series of pinch feed rollers provided with means

for rotating same, and a series of pressure heads carrying rollers which exert rolling pressure against the leather as it is fed, provided with means for oscillating said pressure heads at substantially right angles to the direction of feeding movement of the pinch rollers, said pressure heads carrying different numbers of rollers.

5. In a leather rolling and setting machine having a spaced series of tables, means for continuously feeding leather flatwise across said tables and means for exerting rolling pressure against said tables at substantially a right angle to the direction of feeding movement of the leather.

10 6. In a leather rolling and setting machine having a spaced series of tables, means for feeding leather flatwise across said tables and means for exerting rolling pressure against said tables at substantially a right angle to the direction of feeding movement of the leather, said latter mentioned means applying pressure first in narrow bands or areas across the leather and subsequently in wider bands or areas.

7. In a leather rolling and setting machine, 25 means for continuously feeding a piece of leather through the machine, and means for applying rolling pressure to the piece at substantially a right angle to the direction of feeding movement.

8. In a leather rolling and setting machine, 30 means for continuously feeding a piece of leather through the machine, and means for applying rolling pressure to the piece at substantially a right angle to the direction of feeding movement, said latter mentioned means comprising a series 35 of pressure heads carrying rollers which, during movement of said leather piece, engage the upper surface thereof.

9. In a leather rolling and setting machine, 40 means for continuously feeding a piece of leather through the machine, and means for applying rolling pressure to the piece at substantially a right angle to the direction of feeding movement, said latter mentioned means comprising a series 45 of pressure heads carrying rollers which during movement of said leather piece engage the upper surface thereof, said series of pressure heads being arranged in sequence with one or more pressure heads carrying a multiple of pressure rollers.
